DEMOUNTABLE STAND

Nicholas Sulentic, Waterloo, Iowa

Application September 9, 1937, Serial No. 163,039

2 Claims. (Cl. 211—128)

My invention relates to improvements in demountable stands or the like, and an important object of my improvements is to provide a supporting device of separable interlocking elements, so related that no other means are required for fastening these elements together than coacting engaging means on the elements themselves and mutually parts thereof, for convenient assemblage or disassemblage, and also for compact packing together of the disassembled parts, for compact storage and inexpensive transportation.

This object I have achieved in the combination of self-locking disassemblable standards and shelving which are herein illustrated in the drawing, described in the specification and in the accompanying claims.

It will be understood, that various changes may be made in the various elements of my invention, their respective shapes and effective coactions and separable self-locking means, without departing from the claims herein.

I have, however, shown two slightly different constructions, in both of which my new coacting and disassemblable engaging and locking means are displayed for like uses, yet differentially in the respective dispositions of the releasably interlocking engaging projections and sockets thereof.

Figs. 1 and 2 are respectively slightly different designs of demountable stands connected in their parts and fastening means according to the principles of my invention, and both in perspective. Fig. 3 is a detail perspective view, on an enlarged scale, of shelf and standard demountable connections according to my invention, with other parts broken away. Fig. 4 is a perspective of the engaging tongues on one of the standards. Fig. 4a is a front elevation showing the impressed pocket or socket part on a shelf flange used for coacting releasable locking engagement with one of the tongues on a standard. Fig. 5 is an enlarged medial vertical section, of a diagrammatic showing of interlocked tongue and pocket means on contacting parts of a standard and shelf, while Fig. 6 is a like view thereof as inverted and employed in some installations.

Fig. 7 is an enlarged inner face view of one of the standards, showing the pressed out tongue as having one side edge shaped with differently inclined parts. Fig. 8 is a cross section of the same standard showing said tongue in side edge elevation. Fig. 9 is an outer face view of a broken away portion of said standard and as covering a shelf wall partially, showing the tongue and slot connection therebetween interlocked at their respectively differently angled edges.

In Fig. 1 is shown a pair of horizontal superposed shelves 4 and 9 respectively, both having rear and side vertically disposed walls as shown at 6 and 10, and at 8 and 9a, and respectively having downturned longitudinal front flanges 5 and 11, but these may if desired be erect like the other wall flanges mentioned, or the forward edges of the shelves may be unflanged if desired. The numerals 1 and 2 refer to corner standards for supporting said shelves and of angle steel preferably, the forward standards 2 being short and releasably secured to the forward standards only, while the rear standards 1 are elongated above the shelf 4 and to support the rear corner walls 8 and 9a of the upper shelf 9.

In Fig. 2 is shown a varied form of double-decked stand in which like angle-bar standards 11 are similarly releasably interlocked with the upraised walls 13 and 15 of the like rectangular shelves 12 and 14 respectively.

Referring now to the other figures, in Fig. 4a a part of an upturned flange 15 for the shelf 14 is shown in elevation as seen from the outside of a standard 11 (Fig. 2), in which a socket is pressed at 17 in the same inwardly to leave its top opening upwardly and its bottom bent inwardly as a stop. In Fig. 4 is shown a perspective of a portion of the standard 11 in whose one side part is pressed inwardly a pair of like superposed tongues 16 cut away from the standard at 30 tops and sides to provide them with a lower end inward shoulder with the tongue projecting thence upwardly spaced from the inner wall of the standard. In Fig. 3 is shown the standard 11, or 1 respectively, showing it releasably interlocked with a shelf 9 as shown in Fig. 1, and in which the tongue 16 of each of a vertically disposed pair thereof has been inserted in a socket 17 of a shelf flange 15 to engage or contact tightly against the inner wall thereof. The said parts 40 as coengaged, may be pressed together by any suitable tools to engage tightly together.

In the particular stand of Fig. 1, the upper shelf 9 is narrower than the lower shelf 4, hence flat bar standards 3 are employed to support the forward corners of the upper shelf, the bars 3 being releasably connected at their upper and lower terminations respectively to inner parts of the side flanges 6 outwardly of the lower shelf 4 by said tongue and socket connections, except 50 that the connections therebetween at the lower parts of the bars 3 are reversed in position as shown in Fig. 6 and at 16b in Fig. 1. The device of Fig. 2 has all of its tongue and socket connections between the shelf flanges and the standards 55

- directed upwardly, as are all of the other connections in Fig. 1 save those shown at 16b. As the device of Fig. 2 will have the loadings of its shelves 12 and 14 exerting downward pressures tending to keep the tongue and socket coacting parts interlocked firmly when in use as carriers, these stands serve as transferable floor stands for displaying goods for convenient access to a salesman in serving a customer.
- 10 The demountable stand of Fig. 1, serves the same purposes, while the lower tongue and socket connections 16b as inverted and shown in Fig. 6 lock their joints at medial places on the side flanges 6 of the lower shelf 4, where the loading 15 on the upper shelf 9 keeps them in coacting locking engagement with the lower shelf 4. There is thus provided a certain opposed coaction between the two sets of joints above and below, to keep the stands rigid in use for carrying relatively 20 heavy loads.

There being no separate locking devices for securing these stand elements together releasably, the constructions are relatively inexpensive to manufacture, and rigid in use. The shelves 25 being easily demountable from the standards, these parts may be stored knocked down in piles, or for carriage at small expense because of decreased shipping bulk.

Said Figures 7, 8 and 9 specifically show the 30 contour of the tongue, and also the related shape of the punched out aperture 17a as also shown in Fig. 4a. Referring to said Figs. 7 and 8, the tongue 16 has one side edge 16b vertical or nearly so, while the lower part 16d of the opposite side 35 edge is inclined inwardly relatively to the first mentioned side edge, and has the upper part of its side edge at 16c inclined at a greater angle inwardly to thus provide a terminally diminished upper terminal 16e for easy insertion as shown 40 in Fig. 9 into the aperture 17a of the shelf wall 15. It will be seen that the aperture 17a has a right-hand side edge 16a, and that when the tongue 16e is inserted as shown in the dotted line of Fig. 9, this terminal 16e may by suitable 45 tools be compressed to close the gap between it and the inner face of the well 11. The frictional coacting engagement or contact between the tongue edge parts 16c and 16d with the abutting

inner edges of the wall 15, will cause the parts at that location to interlock wedgingly horizontally at and near the junction of the tongue edge parts 16c and 16d, so that the stand in either case may be lifted without separation of its parts, and sustain much strain without becoming loose, as when being lifted.

5 The same result occurs when some of the coacting tongue and slot features, as shown in Fig. 1 at 16b as reversed in relative positions, remain 10 locked wedgingly as against strains either up or down vertically.

The shapes of the tongues, and of the slots 17a, 15 may be otherwise designed or varied from those shown, without departing from the said principles of my invention.

I claim:

1. In a device of the character described, a carrier member and a second carrier member spaced therefrom upwardly, said members having respectively pressed-out open-top, closed bottom and side-walled socket parts projecting inwardly, and standard members contacting with said carrier members and having pressed-out tongue parts inserted in and releasably interlocked angularly at one side edge with said pressed-out socket parts, the pairs of tongue and socket parts connecting the one carrier member to the standard members being reversed in position with respect to the tongue and socket parts connecting the other carrier to the standard members for opposite separation of the two carriers with respect to the standard members.

2. In a device of the character described, a carrier member and a second carrier member spaced therefrom upwardly, said members having respectively pressed-out open-top, closed bottom and side-walled socket parts projecting inwardly, each socket part having one side wall inclined upwardly inwardly relatively to the opposite side wall thereof, and standard members contacting with said carrier members and having pressed-out tongue parts, each tongue part having one side wall inclined toward the other side wall at a different and lesser angle terminally, and releasably interlocked at its wider angle with the abutting side wall of the receiving socket part.

NICHOLAS SULENTIC.
